LACE LOOM

Robert A. Kennedy and Carmie A. Kennedy,
Birmingham, Mich.

Application October 5, 1948, Serial No. 52,884

3 Claims. (Cl. 66—1)

1

This invention relates to crocheting and weaving devices capable of being held in the hand for supporting lace and the like, and particularly to a manual lace loom.

The main object of our invention is to provide a manually-held means for supporting lace work while operating upon the latter with a crocheting needle.

Another object is to provide manually-held adjustable means for supporting and periodically shifting and taking up hairpin lace and Maltese crochet as it is operated upon and thereby increased in length.

A further object is to have such means of the mentioned character which is provided with clamping facilities for holding finished hairpin lace out of the way and presenting a clear field of operation for working upon the lace.

It is also an object to provide the mentioned means in the form of a loom which is of simple construction and consists of but three parts so arranged and associated as to be practically proof against getting out of order and to insure making hairpin lace of uniform width at all times.

A practical object is, of course, to make a manual lace loom of this character which is easy to make and use and so reasonable in cost as to encourage wide sales and distribution thereof.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a plan view of a lace loom made according to the invention and embodying the same in a practical form;

Figure 2 is a side elevation of the same lace loom looking from the bottom in Figure 1;

Figure 3 illustrates the reverse side or bottom plan view of the loom of Figure 1;

Figure 4 is a longitudinal section of the loom taken on line 4—4 in Figure 3;

Figure 5 is an enlarged transverse section taken on line 5—5 in Figure 2;

Figure 6 is a short length of hairpin lace made upon the loom of the preceding figures.

In the various views the same reference numerals indicate the same or like parts.

When crocheting lace, and especially hairpin lace, it is highly desirable, though difficult, to make the lace uniform in width throughout and of any great length. It is obviously, also, de-

2

sirable to be able to support the lace being made on some means facilitating the production of such lace and holding the latter in well supported position to prevent slipping or shifting of the lace and thereby providing a firm foundation for the work being done in the field of operation.

Upon considering this problem, it has occurred to us that a longitudinally-adjustable loom should be available for making hairpin lace, and as a result we have succeeded in producing a manual lace loom for quickly making uniform hairpin lace of great length, as will now be more fully described.

Hence, in the practice of our invention, and referring again to the drawing, a loom, generally indicated at 1, primarily includes a forked frame 8 consisting of a pair of long straight rods 9 and 10 connected together at one end of each by an intermediate integral yoke portion 11, the length of the two rods 9 and 10 being equal and being of any practical length desired according to the maximum length intended for the lace to be made upon the device. Slidably mounted upon the two rods 9 and 10 forming the limbs of the fork-shaped frame 8 is a box-shaped binder 12 consisting of a substantially flat plate 13 having two opposite longitudinal edges thereof bent up at right angles therefrom in substantial parallelism to form a pair of side walls 14 and 15, the side walls 14 and 15 fitting slidably upon the outside of rods 9 and 10 and serving to prevent the latter from becoming separated during use of the device. Between the side walls 14 and 15 of the binder 12 is mounted a spring latch 16 provided at the rear end thereof with a pair of outwardly-projecting pivot lugs 17, 18 extending laterally through a pair of elongated slots 19 and 20 in the rear portions of side walls 14 and 15 of the binder, respectively. Intermediate the ends thereof, the spring latch 16 is bent inwardly to provide a depressed portion 21 adapted to engage frictionally against the upper or adjacent sides of the rods or limbs 9 and 10 of the fork frame, as will be further explained. At the forward end of the latch spring 16 is a downwardly-directed locking tongue 22 which is sufficiently narrow to extend down between rods 9 and 10 without contact therewith, but normally in closed position, being disposed close to the forward end 23 of plate 13 on binder 12. At the sides of the mentioned forward end of latch spring 16 are a pair of further lugs 24, 25 adapted to engage beneath a pair of overhanging, forwardly-directed retaining lugs 26, 27 upon the

upper corners of the forward ends of side walls 14 and 15, the ends of said walls being recessed, as indicated at 28 in Figure 2, to receive the lugs 24 and 25 of latch spring 16 beneath the retaining lugs 26 and 27 when the latch spring is disposed in its rearward withdrawn position. Inasmuch as the two rear slots 19 and 20 are elongated and the pivot lugs 17 and 18 at the rear end of the latch spring are normally withdrawn into the rear ends of these slots, it is self-evident that if the fingers are applied to the latch spring and the latter slipped forwardly so that the retaining lugs 24 and 25 are shifted beyond the forward ends of lugs 26 and 27 on the side walls 14 and 15, the spring lugs 24 and 25 will be released therefrom and the spring will be released at the forward end in such manner as to be swingable to open position about the pivot lugs 17 and 18. The latch spring 16 being a bent leaf spring with the intermediate depressed portion 21 bearing upon both rods or fork limbs 9 and 10 of the forked hairpin frame 8, the resiliency of the spring itself will tend to snap the forward end of the spring free of the retaining lugs 26 and 27 when lugs 24 and 25 are released therefrom. The latter lugs extend sufficiently far outside the side walls 14 and 15 so that the fingers may be used to directly engage these side lugs in order to release the latch spring when this is to be done in order to pass a section of lace, such as partially shown in Figure 6, rearwardly through the binder when a sufficient length thereof has been crocheted to require such rearward movement for obtaining further clearance at the left end or open portion of the hairpin frame, indicated at 22.

The arrangement is such that the binder 12 is normally locked in position by friction upon the two limbs 9 and 10 of the hairpin frame 8 so that the ends 29 and 30 of said rods or limbs extend two to three inches from the forward end of the binder, the lace being generally of the type known as hairpin lace or Maltese crochet, of which a small section is shown in Figure 6, the loops 31, 32 being mounted on the ends 29 and 30, respectively, of rods 9 and 10 and the loose end 33 worked by means of a crochet needle first on one rod and then the other and intermediately knotted by means of the needle in such fashion as to continuously increase the length of the lace. When this length has been moved toward the forward end 22 of the binder 12 and threatens to become so crowded toward the ends 29 and 30 of rods 9 and 10 that further work is difficult, the binder is opened by releasing latch spring 16 by the fingers, preferably applied to lugs 24 and 25. Then the spring shifted forwardly while the binder 12 is held between the fingers and the lace then pushed beneath the latch spring into the binder so that the finished portion of the lace upon which the work is being done is spaced some two inches from the ends 29 and 30 and the latch spring then closed down upon the lace and moved rearwardly to re-engage lugs 24 and 25 beneath the forwardly-extending retaining lugs 26 and 27 of the binder when the crocheting may proceed until a further shift of the lace is required. It is evident that when latch spring 16 is raised, the lace may be slid along the rods or limbs 9 and 10 rearwardly even past the binder and crowded rearwardly toward the yoke or connecting member 11 and therefore the work may continue until a considerable length of lace has been produced, and in fact, until the latter has been made up to the very

ends 29 and 30 of limbs or arms 9 and 10. In fact, the entire lace may be slid off of the hairpin frame and then a few loops at the forward end of the lace where the work is being done may again be slid on the ends 29 and 30 independently of the binder and the work continued until the few loops have been augmented by an additional number just made and engaging in crowded fashion against the front end 22 of the binder, and the latter may be released just to shift the same rearwardly a short distance in order to make room for a further length of lace to be made. In any event, it is intended that normally the binder is to occupy a position substantially two and a half to three inches from the ends 29 and 30 of the rods or limbs 9 and 10, but not at any considerably greater distance in order to use the binder as a means for retaining the arms or rods 9 and 10 spaced accurately at a predetermined distance apart and prevent separation thereof in order to produce a lace of uniform width. The end tongue 22 upon the forward end of spring latch 16 is a sliding fit between rods 9 and 10 and contributes to maintenance of the accurate spaced relation of these rods by preventing them from being drawn together by the lace during crocheting.

Obviously, the hairpin frame 8 may be made of any length desired, and in fact, the entire device may be made of any size suitable for the type of lace intended to be made. The spring latch 16 is preferably made of resilient metal, such as steel or the like, while the binder is also made of any suitable metal, and the same is true of the hairpin or forked frame 8, and the latter preferably made smooth so that the lace may readily slide thereon when the same is shifted.

Manifestly, variations may be resorted to and parts and features may be modified or used without others within the scope of the appended claims.

Having now fully described our invention, we claim:

1. A lace loom including a forked or hairpin frame having a pair of parallel rods forming the limbs or arms thereof and an intermediate yoke portion integrally interconnecting the rods at one end of each, a binder adjustably mounted upon the rods, means upon the binder for preventing spreading of said rods, and a movable member adjustably mounted upon said binder and having a portion normally extending between said rods and preventing them from being drawn together during use.

2. A lace loom including a forked or hairpin frame having a pair of parallel rods forming the limbs or arms thereof and an intermediate yoke portion inter-connecting the rods at one end of each, a binder adjustably mounted upon the rods, means upon the binder for preventing spreading of said rods, a movable member adjustably mounted upon said binder and having a portion normally extending between said rods and preventing them from being drawn together during use, and inter-engaging means on said movable member ad said binder for securing the movable member to said binder.

3. A lace loom including a forked or hairpin frame having a pair of parallel rods forming the limbs or arms thereof and an intermediate yoke portion inter-connecting the rods at one end of each, a binder adjustably mounted upon the rods, said binder embodying a plate and a pair of side walls carried by said plate, the rods of the frame being positioned within the side walls and engag-

ing the latter, a latch member positioned between said side walls and having one end pivotally mounted on said side walls, said latch member having a portion normally extending between said rods and preventing them from being drawn together during use, and coating lugs on the other end of said latch member and the adjacent ends of said side walls for securing said latch member to said side walls.
